UNITED STATES PATENT OFFICE

148,960

DESIGN FOR A CHILD'S TRAINING CHAIR
OR SIMILAR ARTICLEAlbert B. Sawyer, Brooklyn, N. Y., assignor to
Plastic Treasures, Inc., New York, N. Y.

Application June 29, 1946, Serial No. 131,165

Term of patent 3½ years

(CL. D4—5)

To all whom it may concern:

Be it known that I, Albert B. Sawyer, a citizen of the United States of America, residing at Brooklyn, New York, county of Kings, and State of New York, have invented a new, original, and ornamental Design for a Child's Training Chair or Similar Article, of which the following is a specification, reference being had to the accompanying drawing, forming a part thereof.

Fig. 1 is a perspective view of a child's training chair, showing my new design;

Fig. 2 is a front elevational view;

Fig. 3 is a side view; and

Fig. 4 is a top plan view.

I claim:
The ornamental design for a child's training chair or similar article, as shown.

ALBERT B. SAWYER.
